UNITED STATES PATENT OFFICE.

PETER M. COLQUHOUN, OF LAKWOOD, OHIO, ASSIGNOR TO THE AMERICAN MULTIGRAPH COMPANY, OF CLEVELAND, OHIO, A CORPORATION OF OHIO.

PRINTING DEVICE.

Application filed December 1, 1926. Serial No. 151,878.

This invention is concerned with means for leveling a portion of a printing form to cause it to stand in surface registration with another portion, as for instance leveling address plates so they may stand the same height to paper with a body form on the same printing member.

My invention is particularly designed for employment of an addressing multigraph. 10 Such machine comprises a rotary drum adapted to carry the body form and a changeable address form, and a rotary platen with which both forms coact. Both the body form and address plate may be compound members 15 consisting of a holding plate with raised projections and embossed printing strips mounted on the projections. I have found that while it is comparatively simple to gage address plates so that they all stand the same height, 20 it is much more difficult to gage a blanket of page size. The present invention enables the page blanket to vary in printing height and the machine to be readily adjusted so that the address plates will register therewith.

25 My invention is hereinafter more fully explained in connection with the drawings, and the essential novel characteristics are summarized in the claims.

In the drawings, Fig. 1 is a vertical trans- 30 verse section through an addressing multigraph equipped with this invention; Fig. 2 is a development of a portion of the printing drum; Fig. 3 is a radial section through the leveling mechanism as indicated by the line 35 3—3 on Fig. 1; Fig. 4 is a fragmentary end view of the printing drum adjacent the address plate channel; Figs. 5 and 6 are transverse vertical sections through the plate leveler, on planes indicated by the lines 5—5 and 40 6—6 respectively on Fig. 3; Fig. 7 is a perspective of a portion of a printing drum with the forms thereon.

As illustrated in Fig. 1, the frame of the multigraph shown comprises a pair of vertical end plates, of which one is shown at 10, 45 and a transverse connecting bed portion 11. Mounted in the end plates is the main shaft 12 carrying a pair of skeleton discs 14 on which is removably mounted segment 15 extending for about half a circumference. The segment is shown as held in place by a spring hook 16 carried thereby and engaging the shaft 12.

Beneath the drum is a platen 17 which 50 acts with the printing service on the drum.

18 indicates feed rollers and 19 is an ejecting device for the paper. The platen, feed rollers and ejecting device are all geared with the drum, by gearing not shown.

A portion of the segment, adjacent one 60 edge, is internally thickened as shown at 20 Figs. 1, 3 and 6, and in this thickened portion is a rectangular recess 21. In this recess is a saddle block 30 on which the address plate A may seat. The under surface of this saddle block is slightly inclined as shown in Fig. 1 and such surface bears against a complementary inclined upper surface on a shim block 35 also occupying the recess. A stud 40 mounted in the saddle block extends radially 70 inward through a slot 41 on the shim block and loosely through a hole 42 in the segment, and within the segment is surrounded by a compression spring 44, adjusted by a nut 45 on the stud. The spring 44 maintains the saddle firmly in position, at the same time it may be adjusted radially in and out by shifting the shim block longitudinally.

Secured to the shim block and extending radially inward is a stud 50 which extends 80 through a slot 51 in the segment. Mounted in this stud is the end of a screw 52; the mounting is shown as effected by a flattened portion of the screw occupying a slot in the stud, and a screw pin 55 locking the parts together. The screw 52 extends loosely through a bracket 60 shown as secured to the inner face of the segment by cap screws 61, Fig. 5. Within a notch 63 in this bracket is mounted 85 a nut 65 on the screw.

The nut 65 has index notches 67 in its periphery, any of which may be occupied by a ball 68 pressed toward the nut by a spring 69 mounted in a recess in the bracket. The inner portion of the nut 65 is accessible for 90 the operator's fingers and by turning it he may force the screw 62 in one direction or the other and thus shift the shim block, thereby adjusting the saddle in or out radially as desired. The spring and ball 69, 68 retain the 100 parts in adjusted position, accordingly, whenever a new blanket is mounted on the drum for the body form, the saddle may be adjusted so that an address plate on it is caused to produce an impression of similar depth to that of 105 the blanket. When once adjusted, the machine is set until the blanket is changed.

The address plate shown at A may be made in accordance with application Serial No. 128,760 filed August 12, 1926, by H. C. Osborn 110

and assigned to my assignee, The American Multigraph Company. In such case, it comprises a trough shaped sheet metal member having parallel corrugations *a* from the top 5 of which extend lateral lips *a'* which stand some distance above the body of the plate and thus adapted to carry embossed printing strips *B* resting thereon and having inward flanged edges which overhang the projections. The edges of the address plate are 10 preferably curled back on themselves as shown on *a''* in Fig. 2. Such curled edges occupy longitudinal recesses beneath suitable overhanging ribs 70 and 71 mounted on the 15 segment.

In Figs. 2 and 3, I have shown an abutment plate 74 resting on the saddle face and having on its under side a block 75 against which a compression spring 76 bears. The address 20 plate is shoved into place from the left hand end of the machine and engaging the plate 74 shoves it toward the right, compressing the spring 76. When the address plate is in printing position, its left end has cleared a 25 finger latch 77 which is pressed radially outward by a spring 79 (Fig. 4) occupying a boss 78 on the latch. At the end of the printing impression finger pressure on the outer face of the boss, forces the latch inward to 30 release the address plate, and the spring 76 discharges the plate into position where it may be readily grasped by the operator.

The blanket which cooperates with the address plate is designated *C*. It comprises a 35 sheet metal member having upstanding corrugations *c* with lateral lips *c'* on which are mounted embossed printing strips *b*. One end of this blanket, as shown, is hooked over the overhanging portion of the longitudinal 40 rib 70, while the other end is anchored to a movable bar 80 carried by spring arms 81 embracing the shaft 12. Screws 83 force the bar 80 away from the segment to tighten the blanket.

45 The drawings show at 90 in Figs. 2 and 7, a sheet metal bridge extending across the address plate channel. Mounted in the printing drum are spools 92 from which extends an inking ribbon 93 which overlies the blanket, bridge and address plate channel and the address plate when in place. It is to be understood that in operation the printing drum is given periodic rotations, and during the 50 pause between consecutive rotations the address plate is discharged and a fresh plate inserted beneath the bridge 90, which supports the ribbon at that region.

I claim:

60 1. In a printing machine, the combination of means for carrying a body form, means for carrying an address form periodically changeable, and means for changing the height-to-paper of the address form to bring it into surface registration with the body 65 form.

2. In a printing machine, the combination of means for carrying a body form, means for carrying a removable address plate including a guideway along which the plate may be slid and means for raising or lowering the support 70 for the address plate to bring the plate into registration with the body form.

3. The combination of a rotary printing drum, means for carrying thereon a form for printing the body of an addressed letter, 75 means to support a changeable address plate, and means for adjusting such support in and out radially.

4. The combination of a rotary printing drum, means for carrying thereon a form 80 for printing the body of an addressed letter, a slideway for a changeable address plate, a supporting saddle in said slideway and means for adjusting the saddle in and out radially.

5. In combination, a rotary printing drum, a flexible blanket, means for locking the same on a portion of the drum, a set of address plates adapted to be positioned one after the other on the drum adjacent the edge of the blanket, and means for adjusting the support 90 of the address plates in and out radially.

6. The combination of a rotary printing drum, a slideway thereon for carrying a removable form slid into place endwise of the drum, and means for adjusting the support 95 for said form in and out radially.

7. The combination of a rotary printing drum, a set of address plates of inverted 100 trough shape adapted to be slid into place, a saddle adapted to engage the intermediate portion of said plate, and means for adjusting the saddle in and out.

8. The combination of a rotary printing drum, a longitudinal slideway thereon, a saddle in said slideway, said drum having ribs with overhanging edges on opposite sides of the saddle whereby an address plate may be held in the slideway on the saddle, and means for adjusting the saddle in and out radially. 105

9. The combination of a printing member having a slideway to receive address plates, a saddle block occupying the slideway and adapted to support such plate, said saddle block having an inclined under face, a shim block with an inclined upper face engaging the saddle block, and means for moving the 115 shim longitudinally.

10. The combination with a set of address plates of inverted channel shape, of a rotary member, a saddle block thereon adapted to support such plates, said saddle block having an inclined inner face, a shim block with an inclined outer face engaging the saddle block, and means for moving the shim block 120 longitudinally.

11. The combination of a rotary printing drum, the saddle on said drum having an inclined inner face, the shim beneath the saddle having a complementary inclined outer 125 130

face, a spring to maintain the saddle on the shim, and mechanism for moving the shim longitudinally.

12. In a printing machine, the combination with a frame having a slideway, of a saddle occupying the slideway, said saddle having an inclined under face, a shim beneath the saddle having a complementary inclined outer face, and a screw and nut couple, one member of which is connected with the shim and the other member of which is provided with means whereby it can be manually rotated.

13. In a printing machine, the combination with a rotary drum having a slideway, of a saddle occupying the slideway, said saddle having an inclined under face, a shim beneath the saddle having a complementary inclined outer face, and a screw and nut couple, one member of which is connected with a shim and the other member of which is mounted in the drum, and a platen adapted to cooperate with an address plate on the slideway.

14. The combination of a rotary printing drum having a surface recess, a shim with an inclined outer face occupying the recess, a saddle with an inclined inner face occupying the recess and resting on the shim, a spring maintaining engagement of the saddle and shim, a screw secured to the shim and a nut on the screw accessible for finger operation within the drum and mounted in a recess in a bracket secured to the inner face of the drum.

15. The combination of a rotary printing drum having a slideway for changeable form, the saddle in said slideway having an inclined inner face, a shim beneath the saddle having a complementary inclined outer face, a stud carried by the saddle extending loosely through the shim, a spring acting on the stud to maintain the saddle on the shim and mechanism for moving the shim longitudinally.

16. The combination of a rotary printing drum having a surface recess, a shim with an inclined outer face occupying the recess, a saddle with an inclined inner face occupying the recess and resting on the shim, a stud secured to the saddle and projecting through a slot in the shim and through an opening in the drum, a compression spring surrounding the stud on the inner side of the drum surface,

a shoulder on the stud bearing against the spring, and mechanism for shifting the shim longitudinally.

17. The combination of a rotary printing drum, a longitudinal recess in the drum extending to one end thereof, inwardly overhanging ribs at opposite sides of the recess, a shim with an inclined outer face occupying the recess, a saddle with a complementary inclined inner face occupying the recess and resting on the shim, means for maintaining the saddle in engagement with the shim, a screw connected with the shim, a nut on the screw rotatably mounted in the drum, said nut having index notches, and a spring detent occupying such notches.

18. The combination of a rotary printing drum, means for securing thereon a printing blanket, a longitudinal recess in the drum adjacent the edge of the blanket, a shim with an inclined outer face occupying the recess, a saddle with a complementary inclined inner face occupying the recess and resting on the shim, said drum being provided with inwardly overhanging ribs at opposite sides of the saddle, means for maintaining the saddle in engagement with the shim, a screw connected with the shim, a bracket on the inner face of the drum having a recess transverse of the screw, a nut in the bracket recess and threaded on the screw, said nut having index notches, and a spring detent occupying any of such notches.

19. In a printing machine, the combination of means for carrying a body form, means for carrying a periodically changeable address form, a movable support for the address form, means for adjusting the position of said support to maintain the address form in surface registration with the body form, and means for locking the support in adjusted position.

20. In a printing machine, the combination with a platen, of a movable printing member provided with means for carrying a body form, and means for carrying an address form, means for changing the height-to-paper of the address form to bring it into surface registration with the body form, and means for locking such adjustment.

In testimony whereof, I hereunto affix my signature.

PETER M. COLQUHOUN.
